UNITED STATES PATENT OFFICE

ANTON MARTIN ANTICH, OF ASBURY PARK, NEW JERSEY, ASSIGNOR OF FORTY PER CENT TO THOMAS SKROZA, OF HARTFORD, CONNECTICUT

WATERLESS GAS HOLDER

Application filed December 1, 1930. Serial No. 499,219.

This invention relates to gas holders and particularly to the waterless type designed to contain a large volume of illuminating gas or the like under pressure and wherein a piston or movable cover is provided to confine the gas and to maintain the pressure.

Such gas holders usually consist of a large, suitably braced, outer holder or tank in which is loosely fitted a movable cover or piston. The peripheral edges of the piston are spaced slightly from the inner surface of the outer tank and a gas-proof seal between the piston and the tank is obtained by the interposition of suitable material such as felt or fabric impregnated with or enclosing sealing material or lubricant or both.

My invention contemplates the provision of means for forming a permanent automatic rolling seal between the piston and the tank, irrespective of the position of the piston, whereby the necessity for the renewal or replacement of sealing material from time to time is obviated, as is the danger of leaking due to the wearing out of or damage to said material.

My invention further contemplates the provision of a sealing device requiring little or no attention and which is efficient and not likely to get out of order. The various objects of my invention will be clear from the description which follows, and from the drawings, in which,

Fig. 1 is a top plan view of a portion of my improved gas holder, partly in section, and partly broken away to show the underlying parts, and showing the sealing means and supports therefor.

Fig. 2 is a vertical section thereof, taken on the line 2—2 of Fig. 1.

Fig. 3 is a top plan view of one half of my improved holder, partly broken away to show a portion of the sealing means.

Fig. 4 is a vertical section of the sealing wheel.

Fig. 5 is a similar section of the anti-friction bearings for the various revoluble shafts, and

Fig. 6 is a front elevation of the outer tank showing particularly, the smooth inner surface thereof.

In that practical embodiment of my invention which I have illustrated by way of example, the outer tank, shell, or holder 10, is built up of various structural steel shapes to the required height and of the required diameter. It will be understood that the outer holder 10 is usually polygonal or circular in cross-section. A description of one section thereof between the columns 11 will suffice for all of said sections, since said sections are identical.

The column 11 is preferably built up of a pair of similar vertical channels 12 and 13, arranged back to back and at the proper angle to form the adjacent ends of the adjacent tank sections. Said channels are secured together at their outer flanges as by means of a series of plates 14, each bent to form the properly angled corner 15 at the center of the column 11, and held in place to form part of the outer face of the tank, by the upright lines of rivets 16 and 17. To the inner flanges 18 and 19 of the channels is secured the inner plate 20 forming part of the inner face of the tank. Said plate is provided with a triangular and preferably inwardly projecting portion 21 suitably rounded at its innermost point or vertex 22. Extending from each of the edges of the portion 21 are the preferably flat or curved vertical angularly disposed extensions 23. If the tank is circular, these extensions are curved, and if polygonal, they are flat. The lines of rivets 24 and 25 serve to secure the extensions 23 to the corresponding inner flanges of the channels 11 and 12. Said rivets 24 and 25 have flat heads as 26 on the inside, the flat heads being counter-sunk into suitable holes in the extensions 23 so as to present a smooth inner surface on the plate 20.

Between the columns 11, the tank is built up by a series of suitably flanged plates 27. Each of said plates 27 comprises the horizontal and comparatively wide upper flange 28 extending from the inside to the outside of the tank, and terminating at each end in a narrower extension 29 inserted between the flanges of the channel. At its extremity, the extension 29 has a vertical downwardly

extending flange as 30, whereby the main flange 28 is secured by suitable rivets 31 to the web of the channel 13. At its outer edge, the upper flange 28 terminates in a downwardly extending flange as 32, secured for part of its length by the rivets 33 to the outer plate 15. The vertical portion 34 of the connecting plate 27 forms the inside of the tank between the extensions 23, and joins the upper 10 flange 28 to the narrower horizontal lower flange 79. Each of the plates 27 shaped and flanged as above described is connected to the upper flange 28 of an adjacent similar section 27 arranged underneath it, as by 15 means of the rivets 35 passing through the wide upper flange 28 of the lower plate 27 and through the narrow lower flange 79 of the adjacent upper plate.

It will be understood that both ends of 20 each of the plates 27 are of substantially identical construction, so that the above description of the end and outside flanges 30 and 32 applies equally well to both ends of said connecting plate. It will further be understood that the vertical face 34 may be of 25 any convenient or desired height and that the sections 27 are arranged one above the other and secured to each other, to the plates 15, and to the columns 11 to form a rigid 30 braced structure having no internal seams except the horizontal seams 36 between the flanges 28 and 79, which seams need not be leak-proof as will be hereinafter pointed out, and except for the vertical seams 37 between 35 the extensions 23 and the plates 27, which seams will now be described. At the terminal vertical edge of the extension 23 of the plate 20 is provided an out-turned vertical flange 38, which is abutted against the similar out-turned vertical flange 39 integral with 40 the vertical face 34. Said flanges 38 and 39 are secured to each other by suitable rivets as 40. The seam 37 on the inner extremities of said flanges 38 and 39 is rendered leak-proof, as by means of solder, welding, or the like, though I have found solder efficient for this purpose and quite easily applied to form 45 a smooth leak-proof seam.

It will further be understood that additional plates may be used on the outside of 50 the tank if desired, to cover the space between the outer flanges 32, or that said plates may be omitted if desired, and that the outer tank may be built up of other arrangements of 55 plates and structural steel shapes, since I do not intend to limit myself to the specific arrangement and construction of the tank just described except as hereinafter specifically claimed, and provided, however, that 60 the projections 21 are provided for engagement with the sealing means in the manner which will be more fully pointed out later. It will further be understood that the plates 15 and 20 and the channels 13 and 12 are 65 continuous and of substantially the entire

height of the outer tank 10 and that said plates and channels may be spliced, if necessary, to attain such height.

Since the tank 10 is of polygonal cross-section, the sealing means for one typical section thereof, and for one of the columns 11 only, need be described, it being understood that such description applies to the remaining columns and the remaining sections, being substantially identical for said remaining sections and columns. Arranged inside 70 of the tank and supported by the pressure of the gas therein is the piston 50. Said piston is suitably shaped, braced and weighted in a manner well-known in the art, and moves upwardly and downwardly as the volume of gas under pressure in the tank varies. The peripheral edge 51 of the piston is spaced a comparatively short distance from the inner face 34 of the tank so as not to contact therewith during its movement. The edge 51 of the piston is further triangularly recessed at spaced points, to provide a clearance space for the reception of the corresponding triangular projections 21 of the columns 11. Said piston furthermore carries the various means for sealing the otherwise open spaces 53 between the edge 51 of the piston and the inner face of the tank. The sealing means will now be described.

Said sealing means comprises as one of its important features, an annular rolling element engaging the inner face 34 of the tank and extending circumferentially about the entire inner surface of said tank and shaped and constructed to fit and to roll against said surface and the projections 21. As illustrated, the rolling element takes the form of an annular tube 54, cylindrical in form, which engages the flat surface 34 and the flat portion of the plate 20. Since the interior axes of the various cylindrical sections 55 of the rolling element or tube are disposed parallel to the corresponding inner surface of the tank, it becomes desirable to join said sections 55, by flexible means permitting rotation or rolling of the tube against the tank as a unit over its entire length. Said means takes the form, as illustrated, of conical connecting sections 59 at the columns.

The tube 54 is preferably formed of suitable airproof and somewhat flexible material, such as the rubber and fabric combination commonly used in flexible hose. A layer as 56 of rubber may be provided at the interior of the tube and reinforced with fabric if desired, and may be covered with an outer layer as 57 of suitable fabric impregnated with rubber, if desired. One or more air valves as 58 of well known type communicate with the interior of the tube. Compressed air may be forced into the tube interior, through the air valves 58 to inflate it to the proper diameter and the proper pressure to maintain said tube in the desired pressed contact with 120 125 130

the surface 34. It will be understood, however, that the tube 54 need not necessarily be flexible or inflatable, provided that the conical ends thereof may be flexed to a sufficient 5 degree to permit the rolling action of the tube. The cylindrical sections 55 are therefore joined by the double conical portions 59, consisting of the joined truncated cones 48 and 49. Each of said portions is somewhat 10 flexible at the narrowest points thereof, but of sufficient thickness and strength to resist substantial distortion under the air pressure in the tube, when such pressure is used, and under the stress put thereupon as the tube 15 rotates. Said portion, however, is sufficiently flexible to extend into pressed engagement with the projection 21 to seal efficiently the space between said projection and the portion 59. It will be noted that as the tube 54 rotates, the cones 48 and 49 approach each 20 other at their innermost points, and spread apart at their outermost points, the flexibility of the connecting portion 47 therebetween permitting this action.

25 The tube 54 is revolvably supported as by means of a series of shafts 60 engaging said tube throughout its entire length, preferably at its lowermost element. The shaft 60 may in turn be revolvably supported by the standards 61 secured to the upper surface of the piston, or may be supported by the piston in any other suitable manner. A suitable elongated bearing 46 is provided in said standards to receive the shaft, it being understood 30 that the cylinder 55 and the bearing 46 are in contact with the shaft 60 throughout their entire lengths, to prevent any gas which escapes through the opening 53 from passing between the shaft 60 and the cylinder 55 or 35 between the bearing and said shaft.

Said cylinder 55 further engages the inner face of the tank and as the piston rises or falls, the entire tube 54 rotates, while remaining in pressed engagement with the tank.

40 In order to force the tube 54 with the desired pressure against the tank and to thereby form a sealing joint therewith, a wide, flexible, endless belt as 62 may be arranged to apply constant, though adjustable pressure, 45 against the tube in the desired direction. The endless belt 62 is supported by the spaced shafts 63, 64 and 65, a section 66 of the belt being bulged inwardly and in engagement with the tube 54. The innermost shaft 63 for the belt 62 is adjustable inwardly and outwardly, to vary the pressure upon the tube, as by means of the adjusting screw 67, supported in the bracket 68, which 50 is in turn suitably secured to the support 69.

55 Suitable anti-friction bearings as 70 are provided at the required points for supporting the shafts 63, 64 and 65. As illustrated in Fig. 5, said bearings 70 may take the form of a shell 71 in which the ball races 72 and 60 73 are inserted with the balls 74 therebe-

tween. It will be understood, however, that roller bearings or other suitable anti-friction bearings may replace the bearings 70 illustrated. The shaft 65 is supported by suitable standards as 75 secured to the upper face 70 of the piston, while the shaft 64 is suitably supported as by the cantilever arm 76 extending outwardly from the support 69, which may also be secured to the upper face 75 of the piston. The bearings 70 for the shaft 63 are adjustably supported by the brackets 68, by means of the adjusting screws 67, while the bearings for the shaft 64 are mounted in the arm 76. In order to aid in maintaining the element 54 in its proper position, I prefer to provide an additional shaft 77 engaging the cylinder 55, and rotated thereby on the movement of the piston. Said shaft 77 is supported by two or more brackets 78, secured to the upper face of the piston, and provided with bearings as 70.

80 It will be seen that by adjusting the screws 67, the length of the section 66 of the belt may be varied, thereby adjusting the pressure which forces the element 54 against the tank and against the shafts 60 and 77. As the piston 50 moves upwardly or downwardly, the frictional engagement of the tube 54 with the inside of the tank causes 85 said tube to rotate, said tube rolling on the shafts 60 and 77 and on the wall of the tank without substantial friction or wear, and causing the belt to move about its supporting shafts 63, 64 and 65. The face of the tank 90 may be greased or otherwise lubricated, if desired, to minimize the friction. The projections 21 of the column enter the recesses 52 of the piston and prevent rotary displacement thereof. Said projection 21 also enters 95 the conical space between the conical connecting portions 48 and 49 of the tube, and effectively seals said space without material wear on the surfaces of said conical portions, 100 since the narrow connecting part 47 is sufficiently flexible to be distorted into its spread position and to be forced outwardly at the time it engages said projection 21.

105 Since the tube 54 is preferably supported above the piston, it is desirable to provide means for sealing the space below the conical portion 59 and between the adjacent ends of adjacent shafts 60, to prevent leakage of gas past and underneath the tube. Said means, 110 as illustrated, takes the form of a bevelled wheel 81 having its surface suitably formed, so that in cross-section, said wheel is of substantially the shape of the cross-section of the conical portions 48 and 49, taken vertically through the axes of the adjacent shafts 60. Each of said shafts 60 is suitably secured to the wheel 81 to permit relative rotation thereof independently of the rotation 115 of the shafts. Toward this end, a ball head 120 as 82 is formed on the extremity of the shaft 125 130

60, and the wheel 81 is provided with a pair of corresponding openings as 83 and 84 of the same diameter as and coaxial of the ball heads 82. Said head enters the openings 5 about half-way, thereby providing two spaced lines of support for the wheel. The shafts 60 being supported against longitudinal movement, the wheel 81 is maintained on and is free to rotate on the ball heads 82, so 10 that the shafts 60 may rotate independently of the rotation of the wheel. The surface 85 of the wheel, however, is made of the proper shape to firmly engage the surfaces of the conical portions 48 and 49 preferably along 15 their lowermost elements, and to prevent the leakage of gas therewith. It will be seen that as the tube 54 rotates when the piston 50 rises or falls, the wheel 81 is rotated on the ball heads 82 by the frictional engagement 20 of the conical portion 59 therewith.

It will be understood that the portion 59 is sufficiently flexible to allow that part thereof which reaches its innermost position, to fold in and to allow said part to be spread 25 out into its stretched position when it reaches and contacts with the projection 21. It will further be seen that the tube 54, as well as those portions 59 of said tube which join the cylindrical sections 55 thereof, are forced 30 by the inflation thereof into proper, firm, though somewhat yieldable engagement with the various supporting parts therefor, and that the projections 21 and the wheel 81 properly seal the space 53 and prevent the 35 passage of gas past the shaft 60 or past the closed geometric figure 86 at which the tube engages the inner surface of the tank. The tube is, of course, annular and endless, and the axis thereof is a geometric figure of 40 closed outline, parallel to the line formed by a horizontal cross-section of the inner surface of the tank.

It will further be seen that due to the 45 rolling action of the tube 54, undue friction upon the parts is avoided and the frequent lubrication and replacement necessary in present types of sealing means is avoided. It will further be seen that the operation of the sealing means is entirely automatic once 50 the tube 54 has been inflated or otherwise forced against the tank surface, and substantially no attention thereto is needed after said means has once been put into operation.

55 While I have shown and described certain preferred embodiments of my invention, it will be understood that I do not intend to limit myself to the specific structure shown and described but intend to claim my invention as broadly as may be permitted by the state of the prior art and the terms of the appended claims.

I claim:

60 1. In a waterless gas holder free from sealing liquid, a tank polygonal in cross-section,

and having columns at the corners thereof, each of said columns comprising a pair of angularly disposed channels, an outer plate joining the outer flanges of said channels, an inner plate secured to said channels and having a central, interiorly extending portion, substantially triangular in cross-section, the body of said tank between said inner plates comprising a series of vertically arranged bent plates secured to said inner plates and to said channels, each of said bent plates having a horizontal portion of substantially the width of the web of the channel, a vertical inner portion depending from the inner edge of said flange and a vertical outer portion depending from the outer edge of said flange, and a second horizontal portion extending outwardly from the lower edge of said vertical portion and of less width than the width of the first-mentioned horizontal portion, a piston closure in the tank, and an annular rolling element carried by said piston closure and engaging the inner surface of said tank and indented at spaced points to fit and engage the triangular projections on said columns to form a leak-proof closure therebetween and adapted to permit rotation of the element as a unit about its annular axis.

2. In a waterless gas holder, a tank comprising columns and plates joining said columns, a vertical extension substantially triangular in cross section projecting inwardly from each of said columns, a piston closure in the tank, and a rolling annular element having spaced indents therein carried by said piston closure and engaging the inner surface of the tank and rolling thereon on the movement of the piston closure, and thereby rotating about its annular axis, the vertical extensions of the columns entering the indents to form a seal therebetween.

3. In a waterless gas holder, a tank having a substantially smooth inner surface, and provided with spaced vertical inwardly extending projections, a piston closure movable in said tank, and an annular rolling element having indents corresponding to the projections and adapted to permit rolling of the element, said element being carried by said piston and in sealing engagement with the inner surface of the tank and with the piston.

4. In a waterless gas holder, a tank, a piston closure movable in said tank, a rolling element carried by said piston closure and movable therewith and engaging the surface of the tank, said element comprising a series of cylinders, and flexible distortable connections between the ends of the cylinders to cause rotation of said cylinders about their respective axes on the rolling of the element, adjustable means including a belt for urging the element into engagement with the tank, and means carried by the piston closure for

supporting said rolling element and in sealing engagement therewith.

5. In a waterless gas holder provided with a tank, and a piston closure providing a gap between the piston and the tank, means for sealing the gap, comprising an annular rolling element provided at spaced intervals with constricted flexible and distortable portions adapted to permit rotation of the element about its annular axis, means for maintaining said element in sealing position, and means for supporting said element for rotation about said axis.

6. In a waterless gas holder free of sealing liquid, a tank having an inner surface substantially in the form of a polygonal prism, a piston closure fitted into the tank and of less diameter than that of said inner surface, a continuous endless member carried by the piston closure and engaging the inner surface of the tank and comprising a series of cylinders joined by constricted distortable members, and means including a belt for urging said member into engagement with said surface, whereby movement of said piston closure causes said member to rotate against said surface.

7. In a waterless gas holder, a tank of substantially polygonal cross-section, a piston closure loosely fitted into said tank and movable therein, an endless revoluble sealing member carried by said piston closure, belt means carried by the piston closure for urging an area of said member of predetermined height and of the entire length of the member into engagement with the inner surface of the tank, and means on the piston closure for revolubly supporting said member and for forming a seal between the member and said last-mentioned means.

8. In a waterless gas holder, a tank, a piston closure, an annular member on the closure contacting throughout the greater part of its length with the inner surface of said tank and forming a gas-proof dry seal between the closure and the tank, spaced conical members on the annular member, correspondingly spaced means on said tank engaging said conical members and free of liquid for preventing leakage of gas therebetween, and means for revolubly supporting the member on the closure.

9. In a waterless gas holder, a tank, spaced upright members on said tank substantially triangular in horizontal section and projecting inwardly of the inner wall of the tank, a piston closure movable in the tank and an endless annular rolling element substantially circular in vertical section and engaging and rolling without sliding on the inner surface of the tank, and having spaced conical portions revoluble with the rolling element and engaging the triangular projections, and means carried by the piston closure for engaging the surface of said rolling element

and for supporting said element for rotation about the interior axis of the circular vertical sections of said element.

10. In a waterless gas holder, a tank having vertical spaced projections on the inner surface thereof, a piston closure shaped to fit said projections and to be guided thereby within the tank, an annular rolling element carried by the piston closure and having portions engaging the inner face of the tank and spaced portions engaging said projections to form a liquidless seal therewith and to cause the element to rotate about its annular axis, and liquidless means between the piston closure and said element for supporting said element and for preventing the passage of gas past said element at points spaced from the tank.

11. In a waterless gas holder, a tank, a piston closure in said tank, a liquidless seal comprising an annular rolling element having spaced indented portions and having a polygonal annular axis, means frictionally engaging and movable by the element for urging said element into engagement with the inner surface of the tank, means in sealing engagement with the element for supporting said element throughout its length except at the indented portions thereof, and liquidless means revoluble independently of said supporting means and carried thereby for engaging the indented portions and forming a seal therewith.

12. In a waterless gas holder, liquidless sealing means comprising an annular rolling element having spaced indented portions, revoluble supporting means engaging the surface of said element and forming a liquidless seal therewith except at the indented portions and a wheel shaped to fit said indented portions and in liquidless sealing engagement with said portions and carried by said revoluble means and revoluble independently of said revoluble means.

13. In a waterless gas holder, a tank, a piston closure movable vertically within the tank and having its peripheral edge spaced from the inner surface of the tank and liquidless means for sealing the circumferential space between the piston closure and the tank, comprising a series of substantially cylindrical rolling members comprising a rolling element engaging the inner face of the tank, and having spaced indented flexible portions adapted to cause the element to roll freely as a unit, means for revolubly supporting said rolling element for rotation about its annular axis, spaced vertical stationary members on the tank projecting inwardly therefrom into sealing engagement with the indented portions of the element, and a revoluble wheel engaging each of said indented portions at points spaced inwardly from said members to prevent gas from passing said element at the wheel.

14. In a waterless gas holder comprising a built-up outer tank and a movable piston closure, a dry seal between the piston closure and the tank comprising a series of similar spaced substantially cylindrical members adapted to contact with the inner surface of the tank and to move thereagainst with pure rolling motion, and means for connecting the ends of the cylinders to permit said rolling motion comprising flexible and distortable members joining the ends of the cylindrical members, and spreading outwardly to its greatest width nearest said inner surface of the tank and contracting to its least width at a diametrically opposite point on the rotation of said cylindrical members, said members forming an annular unit capable of rotation about its internal annular axis substantially free of torsion.
15. In a waterless gas holder, the combination with a piston closure of a dry seal therefor comprising an endless annular member of circular vertical section throughout,

said member comprising a series of substantially cylindrical members arranged in the form of a polygon and spaced apart at their ends, and flexible distortable connections for said ends adapted to permit pure rolling 70 movement of the annular member against the inner wall of the holder without substantial torsion or sliding.

16. In a waterless gas holder free of sealing liquid and including a tank and a piston closure, a device for sealing the gap between the piston closure and the tank comprising an annular inflatable tube, and means on the closure for supporting said tube in position to close the gap, said tube comprising a 75 series of spaced cylinders arranged so that their axes form the sides of a polygon, and distortable connections between the ends of the cylinders to complete the tube and to permit the cylinders and the connections to 80 rotate about their respective axes.
